UNITED STATES PATENT OFFICE.

FRANK W. ROSENGREN, OF CHICAGO, ILLINOIS.

GASEOUS-FUEL HEATER.

Application filed July 28, 1924. Serial No. 728,525.

The invention relates to gaseous fuel heaters.

One object of the invention is to provide an improved construction of perforated burner-member which is formed so that it will not readily burn out. Another object of the invention is to provide an improved construction in which the generator-pipe is separately formed from the casing so as to prevent excessive heating thereof which causes carbonization while being heated sufficiently for efficient generation. Other objects of the invention will appear from the detailed description.

The invention consists in the several novel features hereinafter set forth and more particularly defined by claims at the conclusion hereof.

In the drawings: Fig. 1 is a plan of a stove embodying the invention. Fig. 2 is a side elevation, parts being shown in section. Fig. 3 is a section on line 3—3 of Fig. 2. Fig. 4 is a perspective of the burner-ring.

The invention is exemplified in a stove comprising a reservoir 6, which serves as a base and is adapted to contain the liquid fuel under pressure, as well understood in the art, a needle-valve 7, suitably connected to the top of the reservoir and for controlling the delivery of the fuel from the reservoir, and a casing or body 8 which is secured to a pipe-section 9, which extends upwardly from the outlet side of the body of valve 7. This casing comprises a downwardly extending portion 10 which is screw-threaded to pipe 9, a laterally extending integral lug 11, in which is formed a port 12 in communication with the pipe 9, and a laterally extending integral lug 13. A vaporizing pipe 14 is separately formed from the casing, extends through lug 13 and is screw-threaded at 15 into the lug 11. This pipe 14 is disposed at one side of the standard-portion 8^a of casing 8. A fitting 16 is screw-threaded at 17 to the front end of generator-pipe 14. This fitting 16 conducts the vapor from pipe 14 laterally and is provided at one end with a jet or nozzle 18 to discharge the vapor into the inlet duct 19, which is formed in a forwardly extending integral, hollow member 8^b of the casing 8. A bushing 20 is threaded into the front end of member 8^b and is secured therein by a screw 21. Nozzle 18 is separately formed from fitting 16, being screw-threaded there-

to, as at 22. The fitting 16 is provided with a screw 23 which, when removed, permits a cleaning tool to be inserted into the fitting. Lug 13 extends laterally from the front portion of the member 8^b of the casing 8, so that the separately formed generator-pipe 14 will be heated by conduction from the casing. By forming the generator-pipe separately from the casing and securing it in lugs 13 and 11, it has been found in practice that the pipe will be sufficiently heated to vaporize the fuel and will not be heated to such a degree that carbon will form therein. Thus, the generator-pipe will be heated sufficiently for efficient vaporization and avoid carbonization of the fuel in the pipe. This has been found to be an important feature in the use of stoves of this type.

The upper end of the casing 8 is extended outwardly, as at 8^c, to form the base of a burner and is flared upwardly and outwardly, as at 8^d. The duct 19 extends upwardly, as at 24, to discharge the vapor upwardly. A central annular upstanding flange 8^e is formed on and integral with the base 8^c. An annular upstanding flange 8^f is also formed in said base to baffle the vapor from the concavo-convex top-plate 25 of the burner towards the burner-ring 26. The side or margin of the burner is formed by this perforated ring 26, which is formed of thin or sheet metal and clamped between a top 25 and base 8^c by a screw 27. The lower margin of this ring is provided with slits 26^a which divide the vapor into jets and its upper portion 26^b is convex in cross-section and extends upwardly and inwardly from its lower slitted margin. In practice, it has been found that when a vertical perforated burner-ring is used, the heat from the jets passes upwardly and burns away the upper portion of this ring. By the formation described, the jets are directed outwardly and away from the upper portion of the ring, so that it will not burn out. In this manner, the life of the burner-ring is greatly prolonged.

A grid 30, for supporting a vessel, is secured on the top of the casing 8 by screws 31. A cup 32, containing asbestos 33, is screw-threaded to the lower end of the casing 8 and serves as a pre-heater for starting the burner. A duct 19^a extends transversely through the underside of member 8^b and is disposed over the cup 32. This duct 110

communicates with the duct 19 and permits the fuel which condenses in duct 19 to drain into the cup 32, as well understood in the art.

5 It is sometimes desirable to use the stove as a blow-torch. When the ring 26 and top-plate 25 and the grid 30, if desired, are removed, the flange 8^c will deliver the vapor in a stream of the proper form for use as a 10 blow-torch.

The operation of the improved heater is as follows: Fuel from the valve 7 will pass through the duct 12, formed in the standard 8^a, and lug 11, which are integral with 15 the casing 8. The vaporizing-pipe 14 is usually formed of comparatively thin metal, so that it can be quickly heated, while the casing is formed of cast metal, which will heat more slowly, but will retain the heat 20 for a longer period. The vapor will pass from pipe 14 through fitting 16 and be discharged through nozzle 18 into the inlet 19; thence it will be directed upwardly against the imperforate top-plate 25 of the burner 25 and thereby deflected outwardly and downwardly to the outside of the baffle 8^c, where it will be divided by the slotted ring-member 26 to form readily inflammable jets. The heat from the lower portion of the jets will 30 heat the rim 8^d, which will be conducted through the casing, so that the standard 8^e thereof and lug 11 will be heated sufficiently to heat the pipe 14 to vaporize the fuel from the valve 7. In passing through the duct 12, 35 the fuel will be heated before it reaches the vaporizing pipe.

The invention thus exemplifies a heater for gaseous fuel in which the vaporizing pipe is heated by and separately formed 40 from, the burner-casing, which is heated by the flames from the burner. This makes it possible to quickly heat the vaporizing-pipe in starting the heater and prevents excessive heating, such as will cause carbon to form 45 in the burner. The convex and inwardly tapered perforated burner-ring increases the life of the burner, so that frequent replacement thereof will not be necessary. The stove may also be used as a blow-torch, when 50 the top-plate and burner-ring are removed.

The invention is not to be understood as restricted to the details set forth, since these may be modified within the scope of the

appended claims, without departing from the spirit and scope of the invention. 55

Having thus described the invention, what I claim as new and desire to secure by Letters Patent, is:

1. In a gaseous fuel-heater, the combination of a casing provided with a duct, means for controllably supplying fuel to said duct, a generator pipe separately formed from the casing and having one of its ends connected to receive fuel from the duct, the central portion of said pipe being spaced 60 from the casing, a lug on the casing and extending laterally therefrom, the central portion of said pipe extending transversely through the lug and being adapted to be heated thereby, a jet for delivering vaporized fuel from said pipe to the casing, and a burner on the top of the casing whereby the latter will be heated. 70

2. In a gaseous fuel-heater, the combination of a casing provided with a duct, means for controllably supplying fuel to said duct, a generator pipe separately formed from the casing and having one of its ends connected to receive fuel from the duct, the central portion of said pipe being spaced 75 from said casing, a lug formed integrally with the casing and extending laterally therefrom, said central portion of the pipe extending transversely through the lug and being adapted to be heated thereby, a jet for delivering vaporized fuel from said pipe to the casing, and a burner on top of the casing whereby the latter will be heated. 80

3. In a gaseous fuel-heater, the combination of a casing provided with a duct, means for controllably supplying fuel to said duct, a generator pipe heated by said casing and having one of its ends secured to receive fuel from the duct, a jet for delivering vaporized fuel from the pipe into the casing, and a burner on top of the casing and comprising a central imperforate top plate and a ring, said ring having an imperforate inwardly and upwardly extending tapered portion and a depending marginal flange, said flange having vertical slots extending to the junction of the flange and the tapered portion. 90

Signed at Chicago, Illinois, this 17th day of July, 1924.

FRANK W. ROSENGREN.
